WEFT-DETECTING MECHANISM FOR LOOMS.

1,220,686.

Specification of Letters Patent. Patented Mar. 27, 1917.

Application filed June 8, 1916. Serial No. 102,569.

To all whom it may concern:

Be it known that I, EPPA H. RYON, a citizen of the United States, residing at Waltham, in the county of Middlesex and 5 State of Massachusetts, have invented a new and useful Weft-Detecting Mechanism for Looms, of which the following is a specification.

This invention relates to weft detecting 10 mechanism for looms, of the type employed to detect substantial exhaustion of the weft in the running shuttle and to cause replacement of the weft carrier before the weft is entirely exhausted.

15 Different forms of detecting mechanism have been heretofore devised for this purpose, and one form of such mechanism comprised a detecting member provided with one or more points or teeth for engagement 20 with the weft windings, which engagement prevented angular movement of the detecting member. The member was therefore carried bodily in the direction of movement of the lay and this bodily movement was 25 utilized to disable or render inoperative the mechanism for changing the weft carrier. When the weft was substantially exhausted, the engaging end of the detecting member would slide along upon the smooth surface 30 of the weft carrier or bobbin instead of being moved bodily therewith, and this absence of bodily movement of the detecting member permitted the actuating mechanism to remain operative.

35 This type of detecting mechanism has not been found entirely satisfactory, as the teeth upon the detecting member have a tendency to abrade and weaken the weft at the point of engagement and furthermore any slight 40 roughness of the weft carrier or bobbin may prevent the sliding movement necessary to render the device operative, even after the weft is substantially exhausted.

It is the object of my invention to improve 45 the construction and mode of operation of weft detecting mechanism of this type, and to render it more positive in its results.

With this object in view, I provide a detecting member which moves easily out of the path of the weft carrier when engaged by the weft thereon, all other parts of the mechanism remaining stationary and inop-

erative until the weft is substantially exhausted. Preferably the detecting member 55 has a smooth and slightly rounded end and swings lightly upon a pivot when engaged by the weft. When the filling is substantially exhausted, the detecting member so engages certain portions of the weft carrier 60 or devices thereon that movement of the member out of the path of the carrier is positively prevented. The member is therefore forced to move bodily with the weft carrier, and through suitable connections, 65 the actuating mechanism is rendered operative.

In the preferred form of my invention the devices which prevent sliding movement of the detecting member comprise one or more 70 grooves turned in the barrel of the weft carrier. This preferred form is shown in the drawings in which—

Figure 1 is a top plan view of a portion of a shuttle and shuttle box, with my improved detecting mechanism associated therewith;

Fig. 2 is a side elevation taken along the line 2—2 in Fig. 1;

Fig. 3 is a detail elevation taken along the line 3—3 in Fig. 1, and

Figs. 4, 5, 6 and 7 show the weft carrier and detecting member in a series of different positions.

Referring to Fig. 1, the weft carrier 10 is mounted in a shuttle 11 which is shown as resting within a shuttle box 12, carried by the lay of the loom. These parts may all be of the usual construction with the exception of the weft carrier 10 which is provided with 90 one or more shouldered grooves 13. These grooves are positioned to engage the end 14^a of a detecting member 14 whenever they are uncovered by the substantial exhaustion of the weft thereon.

The member 14 is pivoted at 15 to a support or carrier 16 which is slidable upon an arm 17 projecting from a bracket 18 which is rigidly secured to the loom frame 19. A light spring 20 engages a projection 21 upon the member 14 and normally holds the member against a stop 22 formed on the support or carrier 16. A rod 23 is fixed to the carrier 16 and extends through a hole in the bracket 18. At its outer end the rod is 105 threaded to receive an adjusting nut 24 and

a check nut 25 by which the extreme rearward position of the detecting member can be adjusted. A coiled spring 26 surrounds the rod 23 and normally maintains the support 16 in its extreme rearward position.

The support 16 is provided with a cam-shaped projection 27 on its lower edge, adapted to engage an arm 28 fixed to a short horizontal shaft 29 pivotally mounted in fixed bearings 30 and 31, carried by or formed on the bracket 18. A second arm 32 is fixed to the shaft 29, and is loosely connected at its upper end with a rod 33 slidable in a hole extending through a fixed stand 34. A coiled spring 35 surrounds the shaft 29, and normally maintains the arms 28 and 32 in the position shown in Fig. 2.

One end of a floating lever 36 is movable in a slot 37 in said stand 34, said lever being connected to control the operation of actuating mechanism for changing the weft carrier in the shuttle. When the parts are in normal position with the carrier 16 in its rearward position, the rod 33 is drawn forward and the slot 37 in the stand 34 is open, thus permitting idle movement of the lever 36 through the slot. The lever 36 corresponds in function to the lever 25 shown and described in my prior Patent No. 972,722, issued to me October 11, 1910, and the actuating mechanism controlled by the lever 36 may be of the type shown and described in said patent.

The operation of my device is best shown in Figs. 4 to 7. Figs. 4 and 5 show the movement of the detecting member when engaged by a weft bobbin having a sufficient supply of weft remaining thereon. The smooth, slightly rounded end 14^a of the detecting member engages the weft, as shown in Fig. 4, and slips along the surface thereof, swinging about its pivot to the position shown in Fig. 5. The support or carrier 16 remains stationary in its rearward position. When the weft is substantially exhausted the grooves 13 will be uncovered and the end 14^a of the member 14 will engage one or the other of these grooves (Fig. 6), being thus positively held against swinging or sliding movement along the weft carrier. As the member can not swing about its pivot it is forced bodily forward with the weft carrier and shuttle, as shown in Fig. 7, and such movement swings the arm 28 in the direction of the arrow *a* in Fig. 2. The arm 32 is thus moved to the left in said figure, and the rod 33 is projected across the slot 37 in the stand 34. The rod in this position prevents free movement of the lever 36, thus changing the effective pivot thereof, and causing the transfer or other actuating mechanism to become operative.

Having thus described my invention it will be evident that changes and modifications can be made therein by those skilled

in the art without departing from the spirit and scope thereof as set forth in the claims, and I do not wish to be otherwise limited to the details herein disclosed.

What I claim is:—

1. In a loom, in combination, a lay, a weft carrier supported in a shuttle carried by said lay, weft detecting mechanism, and normally inoperative actuating mechanism controlled thereby, said detecting mechanism comprising a movable support and a detecting member mounted thereon and also movable relatively to said support when engaged by weft on said weft carrier, said weft carrier being provided with devices which, when substantially uncovered by removal of the weft thereover, engage said member and prevent such relative movement thereof, whereby said member and support are moved bodily with said weft carrier and said actuating mechanism is rendered operative. 70

2. In a loom, in combination, a lay, a weft carrier supported in a shuttle carried by said lay, weft detecting mechanism, and normally inoperative actuating mechanism controlled thereby, said detecting mechanism comprising a support movable in a fixed path, a detecting member pivoted thereto, a spring to hold said member normally in operative position, said member swinging 95 freely about its pivot when engaged by weft on the weft carrier, and devices on said weft carrier effective to positively prevent such swinging movement when the weft is substantially exhausted, whereby said member and support are moved bodily with said weft carrier and said actuating mechanism is rendered operative. 100

3. In a loom, a weft carrier and weft detecting mechanism comprising a detecting member positioned to engage said weft carrier, normally inoperative actuating mechanism controlled thereby, a support for said member, said member having an inoperative movement independent of said support and axial of said carrier and being also movable with said support transversely of said carrier to render said actuating mechanism operative when said independent inoperative movement is prevented, and means to prevent said inoperative axial movement of said member when the weft on said carrier is substantially exhausted. 110

4. In a loom, a weft carrier and weft detecting mechanism comprising a detecting member positioned to engage said weft carrier, and normally inoperative actuating mechanism controlled thereby, said member normally engaging the weft on said carrier and slipping thereover, and said carrier having provision thereon effective to prevent such slipping of said member when the weft thereon is substantially exhausted. 120

5. In a loom, a weft carrier and weft detecting mechanism comprising a detecting 130

member, a slide upon which said member is pivoted, and actuating mechanism controlled in its operation by said slide, the engaging portion of said member slipping longitudinally of said weft carrier when engaged by a sufficient supply of weft thereon, and said weft carrier having provision

thereon effective to prevent such slipping of said member along the weft carrier when the weft thereon is substantially exhausted. 10

In testimony whereof I have hereunto set my hand.

EPPA H. RYON.
